ATTORNEY

UNITED STATES PATENT OFFICE.

ERNEST W. MEYER, OF NEW YORK, N. Y.

DOOR-LATCH.

1,054,978.

Specification of Letters Patent.

Patented Mar. 4, 1913.

Application filed November 16, 1912. Serial No. 731,652

To all whom it may concern:

Be it known that I, ERNEST W. MEYER, a citizen of the United States, and a resident of the city, county, and State of New York, have invented certain new and useful Improvements in Door-Latches, of which the following is a specification, reference being had to the accompanying drawings, forming a part thereof.

10 My invention relates to means for locking doors, windows or similar devices which are arranged in pairs.

15 The object of my invention is to provide a simple and compact means of the aforementioned character that shall be particularly applicable to double doors and shall hold one of the doors in closed position and lock it in its closed position when the other door is closed.

20 Figure 1 of the accompanying drawings is an elevation of a door frame and double doors equipped with the lock of my invention, certain of the parts being broken away to disclose one of the locks. Fig. 2 is a plan view on a larger scale, of a portion of the base and doors, the latter being swung open slightly. Fig. 3 is a view corresponding to Fig. 2 with the doors closed and the pins, which form parts of the lock at the top of 25 the door, shown in cross section. Fig. 4 is a sectional elevation of a portion of the top of the door frame at right angles to Fig. 1.

Like characters of reference designate corresponding parts in all the figures.

30 Referring to the drawings, the structure here shown comprises a door frame or cabinet having a base 10, side members 11 and 12, a top having a front strip 13, a pair of doors 15 and 16 which are respectively 35 swung from the side members 11 and 12 by hinges 17 and 18 and locks 19 at the top and base, only the top one being shown in Fig. 1. The door 16 may be provided with a strip 20 which overlaps the adjacent edge 45 of the door 15. Each of the locks 19 comprises a plate 30 to which a pawl 31 is pivotally secured by a pin 32, and cams 33 and 34. The plate 30 is fitted into a recess either in the base 10 or the front strip 13 as the 50 case may be and the pawl 31 is located under the plate in the recess and is provided with outwardly projecting pins 35 and 36 which extend through slots 37 and 38 in the plate. The arrangement of parts is such 55 that when the plate is mounted in position it is flush with the surface of the member in

which it is embedded except for the pins 35 and 36 which project slightly beyond said surface.

The cams 33 and 34 are respectively embedded in the edges of the doors 15 and 16 and are adapted to coöperate with the pins 35 and 36 as hereinafter pointed out. The cam 33 consists of a small plate having notches 40 and 41 and an intermediate 60 tongue 42. The outline of the notch 41 and the adjacent surface of the tongue form a reverse curve while the surface of the tongue adjacent to the notch 40 is a straight line, which forms an acute angle with the 65 plane of the door. The cam 34 consists of a plate which is provided with a single 70 notch 45.

The slots 37 and 38 in the plate 30 permit a limited rotative adjustment of the 75 pawl 31 about the pin 32 as an axis.

The operation of the lock is as follows: Assuming that the doors are open and the pawl occupies the position in which it is 80 illustrated in Fig. 2, if the door 15 is swung closed the straight surface 46 of the tongue 42 will engage the pin 35 and will swing the pawl 31 into its opposite position, the pin 36 riding over the reverse curved surface 47 85 into the notch 41. If the pawl does not happen to be in the position in which it is shown in Fig. 3 when the door 15 is swung against it, the inner portion of the reverse curve 47 will strike against the pin 36 to force it over to the right and bring the parts into 90 proper position for the straight edge 46 to engage pin 35. The pin projections of the pawl limit the inward swing of the door 15 and hold it in its closed position. But this is not a positive hold because the outer portion of the reverse curve 47 is so shaped as 95 to force the pin 36 over to the right when a sufficient outward pull is exerted upon the door 15. If however, the door 16 is closed, the pin 36 falls into the notch 45, which is 100 relatively shallow thereby holding the door 16 in the closed position without locking it and positively locking the door 16 closed since the notch 41 is relatively deep. The parts now occupy the position shown in 105 Fig. 3 and it is only necessary to lock the door 16 to the door 15 in any well known manner such as an ordinary bolt lock in order to lock both of the doors securely in 110 their closed positions.

As shown in Fig. 4, I prefer to enlarge the outer ends of the pins 35 and 36 in or-

der to provide shoulders 48 which assist in holding the pawl 31 close to the plate 30 without interfering with its rotative movement.

5 The lock of my invention is of special utility and advantage because it comprises a very few simple parts which may be assembled without difficulty. The use of springs is entirely avoided so that there is 10 nothing to get out of order. The plate 30 is comparatively small and together with the pawl 31 is very thin so that it is only necessary to provide a shallow recess to receive it. It is no wider than the thickness 15 of an ordinary door. The cams 33 and 34 have only the thickness of sheet metal and are so narrow that they do not extend beyond the edges of very thin doors. Blocks or special reinforcements are rendered superfluous so that the installation of 20 the device is easy and may be done with comparatively unskilled labor. At the same time the doors are locked very securely in position when both are closed and locked 25 together. When they are not locked together they will remain in the closed position until some pull is exerted on the right hand door. When this door is opened, the other door may be pulled open without releasing 30 or operating any latches or locks.

While I have referred to the left and right hand doors and the top and bottom of the frame these terms are relative and are used only for convenience since the 35 lock may be utilized with doors, windows and other devices which lie in either vertical, oblique or horizontal planes, and since the doors may be readily arranged to close in any desired order. It is also obvious that 40 it is not necessary to have these locks at both top and bottom of the doors.

What I claim is:

1. The combination with a base, a top and hinge-supported members, of a pivoted 45 pawl embedded in one of the stationary members and having outwardly extending projections and a pair of cams embedded in the hinge-supported members and adapted to coöperate with the pawl projections 50 to lock one hinge-supported member and to hold the other in position when both are closed.

2. The combination with a door frame comprising base, top and side members and

a pair of doors hinged to the side members, 55 of a pivoted pawl embedded in one of the members and having pin projections extending beyond the surface of the member and a pair of cams embedded in the respective door edges, one having a tongue projection 60 which is adapted to produce a rotative adjustment of the pawl when its door is closed and the other of which is provided with a shallow notch which holds the pawl in the position to which it is swung when the first 65 door is closed.

3. The combination with a door frame comprising a top having a front strip, a base and a pair of side members, and a pair of doors hinged to the respective side members, of a slotted plate embedded in the base, 70 a pawl pivotally mounted on the inner surface of the plate and having pins that project outwardly through the slots, a cam comprising a plate, notched to provide a 75 tongue and secured to the edge of one door and a second cam having a shallow notch and secured to the edge of the other door, said slots being arranged to permit a limited rotative movement of the pawl, said tongue 80 being adapted to coöperate with the pin to swing the pawl from one position to another as its door is opened and closed and the other cam being adapted to coöperate with one pin to hold its door in position 85 and to lock the other door in position when both are closed.

4. A lock for double doors comprising a stationary plate having a pawl pivoted thereon and circumferentially curved slots 90 coaxial with the pawl pins secured to the pawl and projecting through the slots, a cam plate adapted to be secured to one door and having notches and an intermediate tongue formed thereby and a cam plate 95 adapted to be secured to the other door and having a relatively shallow notch, said tongue being adapted to extend between and coöperate with the pins to swing the pawl on its axis and the shallow notch being adapted to coöperate with one of the pins to lock the pawl in one position. 100

In witness whereof, I have hereunto set my hand this 15 day of November, 1912.

ERNEST W. MEYER.
